REFRIGERATOR

Hubert D. Bennett, Toledo, Ohio, assignor to
Toledo Scale Manufacturing Company, a cor-
poration of New Jersey

Application May 3, 1935, Serial No. 19,647

7 Claims. (Cl. 62—89)

In refrigerators as heretofore constructed the temperature of the entire interior rises nearly to that of the exterior due to the spilling of the cold air from the refrigerator and its replacement by warm air from outside whenever the refrigerator is opened for access to the contents. Such frequent elevation of interior temperature interferes with proper food preservation and results in considerable waste of ice or power.

10 The principal object of this invention is to provide a refrigerator constructed in a novel and convenient manner, which may have drawers that can be opened and closed without loss of cold air.

More specific objects and advantages are apparent from the description, in which reference is had to the accompanying drawings illustrating a preferred embodiment of the invention.

Figure I of the drawings is an elevation of a refrigerator embodying my invention, showing an upper and a middle drawer pulled out.

20 Figure II is a vertical section taken on the line II—II of Figure I.

Figure III is a fragmentary vertical section taken on the line III—III of Figure I.

25 Figure IV is a fragmentary horizontal section taken on the line IV—IV of Figure I.

These specific drawings and the specific description that follows are to disclose and illustrate the invention, and are not to impose limitations upon the claims.

30 The refrigerator may be made in two or more sections to facilitate manufacture, transportation and assembly. One of the sections may be in the form of a closure section 10, preferably located at the bottom of the refrigerator, so that the other section or sections rest upon it. In the form of refrigerator illustrated there are three intermediate sections 11, 12, 13 resting upon the bottom section 10, and another closure section at the 40 top.

The top section 14 may be provided with means for cooling the air in the refrigerator, such as an evaporator 15 operated by a refrigerating unit located in a rear compartment 16. Beneath the 45 evaporator 15, brackets 17 may be provided for supporting a drip-pan 18 that breaks up direct downward currents of air beneath the evaporator to produce uniform cooling of the top section 14.

50 Warm air from below passes between the insulated side walls 19 of the top section and two inner sheets 20 that are fixed in the top section and are bent over at their tops to lead the air along the insulated top wall 21 to a point above the evaporator 15. To give access to storage

space in the top section 14 an insulated door 22 is provided.

The sections are preferably held together by gravity alone with gaskets 23 interposed between them, as shown in Figure III, made of compressible material to ensure a tight fit. An overlapping bead 24 formed from the metal of the outer shell of one of two adjacent sections improves the appearance of the joint. In order not to provide a conductive path for heat from the exterior to the interior of the refrigerator, the meeting edges of the sections may be formed of a strip 25 of a thermally insulating material such as wood rather than of metal.

15 The first intermediate section 11 may be provided with one or more compartments 26 partitioned off from the rest of the refrigerator. If the compartments extend the full depth of the section, they may have flanges 27 surrounding their front and rear ends for attachment to the 20 front and rear walls of the section, as shown in Figure IV. In the other figures of the drawings most of the flanges 27 are omitted for the sake of clearness.

25 Two apertures 28 may be provided in the top of the compartments for circulation of air that is bypassed by means of baffles 29. The baffles may have strips 30 of flexible material mounted along their upper edges, fitting against portions of the section above, which portions in this case 30 are the bottoms of similar compartments in the section above. Whatever may be the type of construction selected, the second section should co-operate with a compartment of the first to establish circulation of the air of the refrigerator 35 through the compartment.

In the third intermediate section 13, compartments 31 may be provided having no apertures, with walls of thermally conducting material. The interior of these compartments thus may be 40 kept cool while food is stored in them out of contact with the air of the rest of the refrigerator. In order to guide into the proper channels air that has circulated around and through the compartments, the lower edges of the inner sheets 20 may carry flexible strips 32 and extend down into 45 contact with the tops of the upper compartments 31.

The food in the compartments is preferably stored in drawers 33 to make it readily accessible. 50 To limit the outward movement of the drawers, stops 34 are provided in the upper compartments. In the case of the apertured compartments, the stops may constitute depending tongues 35 formed in the punching of the apertures 28. Means may 55

be provided for conducting air from the main chamber through the drawers, such as the apertures 28, baffles 29, and baffles 36 in the drawers.

The drawers 33 are preferably closed off from their compartments so that the air in the drawers is not disturbed when they are opened and closed. In order that all the air entering the compartments when the drawers are opened may be displaced when they are closed, they are made substantially large enough to fill the compartments. Insulated outer ends 37 may be provided if the compartments have separate openings to the exterior that are closed by the drawers.

In case the drawers have open tops, and are maintained closed off from the compartments by means of portions of the compartments, such as the top walls, cooperating with the open tops of the drawers, passages should be provided for flow of air into and out of the compartments without disturbing the air in the rest of the refrigerator as the drawers are opened and closed. Such passages may be formed by spacing the drawers from the bottoms of the compartments with thick slides 38. The passages are not necessary if the drawer has a closed top because the entering air would then not disturb the air in the drawer.

Although the two bottom compartments are shown identical, and the second intermediate section is shown identical with the first intermediate section for the purpose of clarity of illustration, each of the compartments may be made ventilated or closed in accordance with desired conditions of the circulating air and the nature of the food to be preserved. The refrigerator may be converted from one type into another and expanded in size with ease, because of the peculiar sectional construction provided. When the drawers are opened and closed, there is no loss of cold air by convection from the drawers or from the main portion of the refrigerator.

Changes in form may be made and various embodiments of the invention may be constructed to meet various conditions.

Having described my invention, I claim:

1. In a refrigerator, a compartment partitioned off from the rest of the refrigerator, an open-top receptacle movable into and out of the compartment, said compartment having a portion that cooperates with the top of the receptacle to maintain the receptacle closed off from the compartment as it is moved outward and inward, and a passage for flow of air into and out of the compartment without disturbance of the air in the receptacle as it is moved in and out.

2. In a refrigerator, a compartment partitioned off from the rest of the refrigerator and having thermally conducting walls, a drawer made of thermally conducting material slidible into and

out of the compartment, and closed off from the compartment, and means for cooling air in the refrigerator for circulation around the exterior of the compartment walls to cool the contents of the drawer.

3. In a refrigerator, a main chamber, a compartment partitioned off from the main chamber and having a separate opening to the exterior, and a drawer slidible into the compartment to displace substantially all the air from the compartment and to close said opening, the drawer being closed off from the compartment tightly enough so that the air in the main chamber and in the drawer is not disturbed when the drawer is opened and closed.

4. In a refrigerator, in combination, a main chamber, a compartment partitioned off from the main chamber, a drawer slidible into the compartment and closed off from the compartment tightly enough so that air in the main chamber and in the drawer is not disturbed when the drawer is opened and closed, and means for conducting air from the main chamber through the drawer, without spilling substantial quantities of the air when the drawer is open.

5. In a refrigerator, a main storage chamber, a compartment partitioned off from the main chamber, and a receptacle of substantial size relative to the main chamber for miscellaneous articles movable into and out of the compartment and closed off from the compartment tightly enough to cause air to rush past the receptacle into and out of the compartment as the receptacle is moved in and out, without disturbing the air in the receptacle or in the main chamber.

6. In a refrigerator, a compartment separated from the rest of the refrigerator, and an open top receptacle movable into and out of the compartment, fitted closely enough against the top of the compartment and sufficiently spaced from a longitudinal wall of the compartment other than the top, to cause air to rush into and out of the compartment as the receptacle is moved in and out, without disturbing the air in the receptacle.

7. In a refrigerator, in combination, a refrigerating section comprising means for cooling the air of the refrigerator, and a variable number of sections forming with the refrigerating section a refrigerator composed of a tier of sections, said sections forming air-tight joints with one another to establish proper circulation of the air in the refrigerator and including a compartment having a drawer mounted therein and slidible therefrom and closed off therefrom tightly enough to cause air to rush past the drawer into and out of the compartment as the drawer is moved in and out, without disturbing the air in the drawer.

HUBERT D. BENNETT.
